LOCKET CONSTRUCTION

Louis C. Mark, Providence, R. I., assignor to New England Glass Works, a partnership consisting of Isaac L. Rice and Alexander Weiner, doing business in Rhode Island

Application December 17, 1938, Serial No. 246,394

4 Claims. (Cl. 63—19)

My present invention relates to the jewelry art, and has particular reference to a locket construction having a plurality of ornament compartments.

5 It is the principal object of my invention to provide a locket of simple construction in which a plurality of ornamental objects or photographs may be placed.

10 It is an additional object of my invention to provide a locket which is easy to manipulate and to open, and which remains open until closed.

15 Another object of my invention is to provide a locket having the above advantages which has a minimum number of readily manufactured and assembled parts.

With the above and other objects and other advantageous features in view, my invention consists of a novel arrangement of parts more fully 20 disclosed in the detailed description following, in conjunction with the accompanying drawing, and more specifically defined in the claims appended hereto.

In the drawing:

25 Fig. 1 is a front elevation of a locket embodying my invention, the parts being closed;

Fig. 2 is a side elevation thereof;

Fig. 3 is a view similar to Fig. 1, the compartments being open;

30 Fig. 4 is a plan view of the base member;

Fig. 5 is a plan view of the inner unit;

Fig. 6 is a section taken along line 6—6 on Fig. 1; and

35 Fig. 7 is a section taken along line 7—7 on Fig. 1.

Conventional pendants and lockets are usually made as thin as possible and are, because of said thinness, extremely difficult to open. The locket of the present invention is designed to 40 provide a plurality of ornament receiving portions adapted to nest together, and to provide a simple and easy arrangement for opening said locket and for latching the parts in closed relation.

45 Referring in detail to the drawing illustrating my invention, the locket 10 generally comprises a base 11 having a hinge cover 12, and housing an auxiliary unit 13 comprising a central portion 14 and two side cover portions 15 and 16 respectively. The base 11 may be of any material and shape, and is preferably arcuate in form and of an ornamental metal such as white metal, which can be readily colored or ornamented. As shown in Fig. 4, the 50 base 11 is provided at its upper edge with an

integral lug 17 having a suitable opening therein for attaching a neck chain or the like. Directly below the lug 17 is an integral eye 18 in which a rectangular latch member 19 is loosely mounted.

The face of the base 11, see Fig. 7, is provided with an integral annular rim 20, and a split rib 20a for positioning the central unit, the lower end of the rim 20 being provided with integral spaced lugs 21 positioned opposite the latch member 19 and forming a journal opening for the pivotal mounting of the cover 22. The cover 22 is rimmed to provide a receptacle for a photograph or other ornament and is of sufficient size to bridge the opening formed by the annular rim 20, the upper end of the cover having an integral upturned lug 23 forming a catch element for releasable engagement with the latch member 19. The center of the base 11 is preferably provided with an integral upstanding detent 24 for securing the auxiliary unit thereto, as hereinabove described.

The auxiliary unit shown in Fig. 5 has its central cup-shape portion 14 of smaller diameter than the annular rib 20a so that it will fit snugly within the base 11. The portion 14 has a central opening 25 to receive the detent 24, which is swaged to lock the parts together, and has seating lugs 26 struck from the right side thereof. The side wing portions 15 and 16 are dished to receive photos or ornaments, and are hinged to the central portion 14 by means of conventional spring hinges 27 and 28 which urge them to open position, the hinges fitting between the split portions 27a and 28a of the rib 20a. The portion 15, to the left, is of slightly smaller diameter than the portion 16 and is adapted to fit within the rim of the central portion 14, the edge thereof resting on the lugs 26. The portion 16, to the right, is provided with an integral finger tab 29. When the auxiliary portion is closed, the wing portion 15 is folded within the central portion 14 with its edge resting on the lugs 26 to space it from the bottom and then the wing portion 16, of slightly greater diameter, is folded over the wing portion 15, the finger tab 29 resting on the hinge 27. The cover 22 is then turned up over the closed auxiliary unit and latched as shown in Fig. 6 by pulling the rectangular latch member 19 over the catch 23 on the cover 22. When the latch member 19 is lifted, the hinge springs press the wing portions outwardly and force the cover 12 to open position as shown in Fig. 3.

It can thus be readily seen that the locket of

the present invention is economical to manufacture and to assemble and provides a plurality of ornament receiving portions which open up for inspection when the latch is released from the catch. A spring-pressed catch and latch arrangement may be used, if desired, and an auxiliary releasable lock may be provided to hold the two wing sections in closed, nested relation; or additional photos or ornament disks may be swivelled to the wing portions adjacent the edges thereof, such and other modifications being within the skill of a jewelry designer. The ornament receiving portions may be flat, or slightly rimmed, to receive a photograph or other insert; or, if preferred, said portions may have a rim with detents to permit snapping engagement of a photograph or ornament carrying disk or disks therein. The invention may be applied to pendants of all types, watch fobs, brooches, pins, and other articles of jewelry.

While I have described a specific constructional embodiment of my invention, and a specific method for assembly, it is obvious that these are merely illustrative, and that changes in the size and shape of the parts, in their relative arrangement and method of assembly, and in the materials used and the ornamentation applied, may be made to suit the requirements for different articles of jewelry, without departing from the spirit and the scope of the invention as defined in the appended claims.

I claim:

1. In an article of jewelry, a cast metal base having a recess, a cover hinged thereto, latch and catch mechanism for releasably retaining said cover in closed position on said base, and an auxiliary unit having a center portion locked

in said base recess, two wing portions hinged to said center portions, said wing portions being resiliently urged to open position.

2. In an article of jewelry, a base, a cover hinged thereto, latch and catch mechanism for releasably retaining said cover in closed position on said base, and an auxiliary unit having a center portion and two wing portions hinged thereto, said wing portions being resiliently urged to open position, said center portion having an opening and said base having a detent projecting through said opening and swaged to lock said unit to said base.

3. In an article of jewelry, a base, a cover hinged thereto, latch and catch mechanism comprising a catch lug on said cover and a latch hinged to said base for releasably retaining said cover in closed position on said base, and an auxiliary unit having a center portion and two wing portions hinged thereto, said wing portions being resiliently urged to open position, said center portion having an opening and said base having a detent projecting through said opening and swaged to lock said unit to said base.

4. In an article of jewelry, a base, a cover hinged thereto, latch and catch mechanism comprising a catch lug on said cover, an eye on said base, and a latch hinged in said eye, for releasably retaining said cover in closed position on said base, and an auxiliary unit having a center portion and two wing portions hinged thereto, said wing portions being resiliently urged to open position, said center portion having an opening and said base having a detent projecting through said opening and swaged to lock said unit to said base.

LOUIS C. MARK.
